UNITED STATES PATENT OFFICE.

DAVID H. BURKEY, OF ALLEGHENY, PENNSYLVANIA.

WEATHER-STRIP.

SPECIFICATION forming part of Letters Patent No. 693,230, dated February 11, 1902.

Application filed November 15, 1901. Serial No. 82,343. (No model.)

To all whom it may concern:

Be it known that I, DAVID H. BURKEY, a citizen of the United States of America, residing at Allegheny, in the county of Allegheny and State of Pennsylvania, have invented certain new and useful Improvements in Weather-Strips, of which the following is a specification, reference being had therein to the accompanying drawings.

10 This invention relates to certain new and useful improvements in weather-strips, particularly to that class adapted to be engaged by the lower edge of a hinged or swinging door, and has for its object to construct a strip of this nature that will be effective in preventing wind, rain, frost, &c., from passing through the crevice ordinarily found underneath hinged or swinging doors.

Briefly described, the invention consists of 20 a metal strip which has beveled sides and is grooved throughout its upper face, in which groove is placed a heavy rubber tube adapted to be engaged by the lower edge of the door to form a seal therewith. The metal strip 25 may, if desired, be countersunk into the floor and only a part of the rubber tube allowed to project above the floor to be engaged by the lower edge of the door. The groove in the strip is made sufficiently deep that packing 30 material of a suitable nature may be placed therein underneath the rubber tube in order to have a greater or less portion of the latter project above the strip.

In describing the invention in detail reference will be had to the accompanying drawings, forming a part of this specification, wherein like numerals of reference will be employed to indicate like parts throughout the several views, and in which—

40 Figure 1 is a detail perspective view of the strip, showing a portion of the door in dotted lines. Fig. 2 is a top plan view of the strip. Fig. 3 is a transverse vertical sectional view thereof. Fig. 4 is a longitudinal sectional view 45 of the strip countersunk in the floor, and Fig. 5 is a transverse vertical sectional view of the same.

In Fig. 1 I show a form of strip adapted to be connected to the top of the floor, and this 50 strip is placed within the doorway. This strip 1 is preferably made of metal and is made with beveled sides 2 and provided with

apertures 3 to receive wood-screws or other suitable fastening means. The strip when it is made in this form is preferably cut away 55 at the ends, so as to form projections 4, which are adapted to abut against the strips secured to the inner faces of the door-frame. This strip is centrally grooved in its upper face throughout its length, which groove 5 is 60 adapted to receive a heavy rubber tube 6. The groove is made sufficiently deep that the rubber tube will lie therein with the greater portion thereof within the groove, and it is also made sufficiently deep to permit the placing 65 of a layer of packing material 7 therein.

In the form of construction shown in Figs. 4 and 5 the strip 1' is countersunk in the floor 2', so that the upper face thereof is flush with the face of the floor. This strip 1' is also provided with a groove 3' in the upper face, throughout the length thereof, to receive the rubber tube 4', underneath which is placed a packing 5'. The thickness of this packing material may be increased or decreased in 75 either of the forms of the strip shown in order to raise or lower the rubber tube in its strip. The rubber tube is made of a heavy material, so that the same will not be damaged when depressed, but will immediately return to its 80 normal condition.

It will be noted that various changes may be made in the details of construction without departing from the general spirit of my invention.

Having fully described my invention, what I claim as new, and desire to secure by Letters Patent, is—

A weather - strip comprising an integral metal strip grooved throughout its length on 90 its upper face, a packing arranged in the bottom of said groove throughout the entire length thereof, a heavy rubber tube fitted in said groove with its bottom engaging the upper face of the packing, the side walls of said 95 groove engaging the sides of said rubber tube and securing the same by frictional contact therewith, substantially as described.

In testimony whereof I affix my signature in the presence of two witnesses.

DAVID H. BURKEY.
